ROPE TRAMWAY

Fredrik Johansen and Elmer J. Lloyd, Worcester,
Mass., assignors to The American Steel and
Wire Company of New Jersey, a corporation of
New Jersey

Application November 25, 1936, Serial No. 112,764

2 Claims. (Cl. 104—87)

This invention relates to improvements in rope tramways and more particularly to a connection adapted to permit the passage of a carrier for an aerial tramway from a rigid overhead rail to a suspended flexible track.

An object of this invention is to permit the passage of a tramway carrier from an overhead fixed rail onto a suspended track cable in a smooth and gradual manner.

10 These and other advantages will become apparent as the disclosure proceeds, in which:

Figure 1 is a side elevation of the movable rail end assembly;

Figure 2 is a section on line II—II of Figure 1;

Figure 3 is a section on line III—III of Figure 1; and

Figure 4 is a section on line IV—IV of Figure 1.

In the drawing, the numeral 2 represents a cast steel movable rail end which is pivotally supported at 3 to the end of a rigid overhead rail or track 4. The rail end 2 is constructed to provide a main body portion of substantially inverted U-shaped cross-section, as shown in Figure 3, to form a carrier engaging surface 5. The end of the movable rail end 2, pivoted to the rigid overhead track 4, is extended beyond the main body portion to provide integral flange members 6 positioned on each side of the rigid overhead track and held in spaced relation to the end of the rigid overhead track by means of filler blocks 7. These filler blocks are suitably secured on each side of the rigid track independent of the pivotal connection between flanges 6 and the rigid track 4. The main body portion of the movable rail end 2 terminates in a flange 8 depending at a point substantially beyond the end of the rigid track 4. The flanges 6, which extend beyond the end of the movable rail end 2, are provided with curved surfaces 9 tapering downwardly toward the free end of the flanges and terminating at their free ends in a plane below the tread surface of the rigid track 4. The movable rail end is pivotally secured to the rigid track at a point above the plane of the flexible track 10 as clearly shown in Figure 2.

The opposite or free end of the movable rail end 2 is provided with upwardly extending flanges 12 which are in a plane below the plane of the flexible track 10, as clearly indicated in Figure 4. In order to retain the free end in proper relationship to the flexible track 10, a filler block 14 is suitably secured between the flanges 12.

55 Under such a construction, it is possible to

permit a gradual transfer of the carrier 15 from the rigid track 4 to the flexible track 10. As the wheels 16, of the carrier 15, approach the end of the rigid track 4, they engage, prior to the end of the track 4, the extended flanges 6 of the 5 movable rail end 2, as shown in Figure 2 of the drawing. The top of these flanges 6 are curved to permit a gradual transfer of the carrier wheels 16 from the rigid overhead rail 4 onto the carrier engaging surface 5 of the movable rail end 10 10 2. The carrier being supported on the surface 5 of the rail end 2 passes over said rail end until it reaches a point substantially adjacent the free end thereof, whereupon it engages the extended flanges 12 prior to being transferred to the flexible track 10. The flanges 12 support the carrier wheels 16 until the tread portion of said wheels, due to the downward pressure caused by the weight of the carrier, engages the top of the flexible track 10, as shown in Figure 4. The 20 weight of the carrier 15 then depresses the flexible track 10 to a slight degree and will continue to run on the flanges 12, due to their downward taper below the plane of the flexible member 10, until the resistance of the flexible track 10 is 25 sufficient to support the load.

The flanges 12, of the movable end member 2, gradually taper downwardly toward their ends to a plane below the normal plane of the flexible track 10 and, due to this curvature, assist in the 30 gradual transfer of the carrier 15 from the movable rail end 2 onto the flexible track 10. Therefore, the carrier 15 has been transferred from the rigid track 4 to the flexible track 10 in a smooth and gradual manner without any impact or jar- 35 ring of the flexible track.

Such a smooth transfer of the carrier from the rigid track to the flexible track overcomes the main difficulties experienced in overhead transfer devices now in use. It eliminates continual 40 pounding of the wires forming the flexible track and lessens the danger of a rupture to the wire constituting the flexible track.

While we have shown and described a specific embodiment of our invention, it will be understood that we do not wish to be limited exactly thereto, since various modifications may be made without departing from the scope of the invention as defined by the following claims.

We claim:

1. In an overhead track construction including a rigid track and a flexible track, a movable rail end of substantially inverted U-shaped construction pivotally supported by said rigid track and interposed between said rigid track and 55

flexible track comprising a main body portion, flanges on each end of said main body portion, said flanges on one end disposed on each side of said rigid track and the flanges on the other end disposed on opposite sides of said flexible track, the top surfaces of said flanges approaching gradually to the level of the tread surfaces of the respective tracks so that a carrier is transferred from said rigid track to said flexible track in a smooth and gradual manner and with no impact on the flexible track.

2. In combination with a rigid track and a flexible track, a movable rail end pivotally supported by said rigid track above the horizontal plane of the flexible track, said movable rail end comprising a main body portion of substantially inverted U-shaped cross-section having a

carrier-engaging surface, integral flanges extending from each end of said main body portion and disposed on opposite sides of said rigid track and flexible track, filler blocks between the rigid track and the flanges disposed on each side thereof, the flanges on both ends of said main body portion having curved faces to conform, with the respective tracks, to the contour of a wheel carrier, the top surfaces of said flanges approaching gradually to the level of the tread surface of the respective tracks so that a carrier is transferred from said rigid track to said flexible track in a smooth and gradual manner devoid of any pounding to said flexible track.
